UNITED STATES PATENT OFFICE.

CHARLES H. LANDENBERGER, OF PHILADELPHIA, PENNSYLVANIA.

DESIGN FOR FABRIC.

Specification forming part of Design No. **6,833**, dated September 2, 1873; application filed June 12, 1873.
[Term of Patent 3½ years.]

To all whom it may concern:

Be it known that I, CHARLES H. LANDENBERGER, of the city and county of Philadelphia, State of Pennsylvania, have invented a Design for a Fabric, of which the following is a specification:

The nature of my design is clearly shown by the figure in the accompanying drawing, which represents a section of the body of the fabric and of part of a stripe upon the same.

The main peculiarity of the design is the transverse ribbing of the fabric at intervals, as represented at *a a*. These ribs are formed by the use of coarse threads in the filling at the desired intervals, they being in the body *A* of the fabric, of a uniform color with the same, but projecting outward from the surface, and having the rounded appearance shown. In the stripe *B*, the center of which is of a checkered pattern, the members are wider and thicker at the points where the ribs occur than in the spaces between the same, thus producing a peculiar and pleasing effect. The stripe *B* consists of the check-

ered center *b*, of a plain stripe, *c*, at either side of the same, and of a narrow bar, *d*, upon one edge. This may form the complete stripe; but I prefer to combine several of the said stripes to form one wider stripe, in which case the spaces *x* between the same should be of a different shade or color from that of the main body of the fabric *A*.

Irrespective of the colors employed, I claim—

1. The design, herein described, for a fabric ornamented by projecting ribs *a* of the character described.
2. The design for the stripe *B*, or for a band composed of an aggregation of such stripes, as described and represented.

In testimony whereof I have signed my name to this specification in the presence of two subscribing witnesses.

CHARLES H. LANDENBERGER.

Witnesses:
